UNITED STATES PATENT OFFICE.

ALBERT BOONE, OF SAWTELLE, CALIFORNIA.

MANIFOLD LOCK.

Application filed September 8, 1922. Serial No. 586,849.

To all whom it may concern:

Be it known that I, ALBERT BOONE, a citizen of the United States, residing at Sawtelle, in the county of Los Angeles and State of California, have invented new and useful Improvements in Manifold Locks, of which the following is a specification.

This invention relates to means for locking certain parts of internal combustion engines, and more particularly internal combustion engines of vehicles.

An object of the invention is to provide improved lock controlled and lock actuated valves for the intake manifolds of gasoline engines, so as to prevent unauthorized use of the motor, thereby reducing the probability of theft of the vehicle in which the motor may be installed.

It is an object to provide a lock controlled valve means which may be utilized in combination with an ordinary or usual throttle or may be combined with a primary throttle. Other objects and advantages will be made manifest in the following specification of an embodiment of the invention illustrated in the accompanying drawings, wherein—

Figure 1 is another form of the invention; and

Figure 2 is a cross section on line 4—4 of Figure 1.

An embodiment of the invention is shown in Figures 1 and 2. A lock casing or pocket 12 is so disposed that a locking barrel 14 is in such position that the cylinder or stem 13 may register with a socket member 11½ formed or provided upon the contiguous end of the usual throttle rock shaft 5 carrying the valve 6. In this case, a key 15 is adapted for connection to the operating mechanism 8 so that the key becomes a part of the mechanism for opening and closing the throttle valve 6 in the ordinary manner.

The key 15 of the throttle valve 6 may be connected to the throttle link or mechanism

8 in any suitable manner, preferably detachably, so that the key can be removed from the lock cylinder. A simple fastening means is shown as including a spring latch 16 engaging over the hooked end of the link 8, this being passed through an aperture in an arm 15½ attached to the key 15.

In order to prevent the possibility of the lock being picked by the employment of a hair pin or some other similar instrument, I provide means for rendering the rotation of the cylinder 13 comparatively difficult so that the employment of relatively fine instruments will be ineffective to rotate the cylinder in effecting an actuation of the valve 10. This means in the present instance comprises a leaf spring 17 secured to the inner side of the lock casing by means of a screw 18 so that the spring bears against the inner end of the cylinder 13 so as to frictionally hold the cylinder against rotation. It will, of course, be understood that by the employment of the key 15 sufficient force may be exerted to overcome the action of the spring and thereby effect rotation of the cylinder over the valve 10.

Further embodiments, modifications and arrangements of the parts may be resorted to within the spirit of the invention as claimed.

I claim:

In combination, a carburetor including a throttle valve, a key controlled lock attached to the valve for opening and closing the same, a throttle actuated link, a key for actuating the lock, and a device providing for the ready attachment and disconnection of the key to the said link and permitting the entire removal of the key from the throttle controlling lock and from the throttle link.

In testimony whereof I have signed my name to this specification.

ALBERT BOONE.
